UNITED STATES PATENT OFFICE.

FERDINAND D. MAGUOLO, OF ST. LOUIS, MISSOURI.

DISPLAY-CABINET.

No. 879,782.

Specification of Letters Patent.

Patented Feb. 18, 1908.

Application filed May 6, 1907. Serial No. 371,986.

To all whom it may concern:

Be it known that I, FERDINAND D. MAGUOLO, a citizen of the United States, and resident of St. Louis, Missouri, have invented 5 certain new and useful Improvements in Display-Cabinets, of which the following is a specification containing a full, clear, and exact description, reference being had to the accompanying drawings, forming a part 10 hereof.

My invention relates to a display cabinet, my object being to construct a simple, compact cabinet to be utilized for displaying goods, and which cabinet is provided with a 15 rotary frame carrying a series of circular shelves which receive the goods to be displayed.

To the above purposes, my invention consists in certain novel features of construction 20 and arrangement of parts, which will be hereinafter more fully set forth, pointed out in the claims, and illustrated in the accompanying drawings, in which:—

Figure 1 is a vertical section taken through 25 the center of a display cabinet of my improved construction; Fig. 2 is a horizontal section taken approximately on the line 2—2 of Fig. 1; Fig. 3 is an enlarged detail section taken on the line 3—3 of Fig. 2; Fig. 4 is an 30 enlarged detail section taken on the line 4—4 of Fig. 2; Fig. 5 is a perspective view of one of the segments which form the circular shelves of the cabinet; Fig. 6 is a plan view 35 of a bearing at the upper end of the rotary frame.

In the construction of the display cabinet, 1 designates a rectangular frame of wood, or metal, the sides, rear wall, and top of which are provided with sections 2, of heavy plate 40 glass; and the front being provided with a pair of hinged doors 3, which open outwardly in order that access may be had to the interior of the cabinet.

The bottom 4 of the cabinet is solid and 45 supported on blocks 5 a suitable distance above the floor or counter.

The body of the rotating member of the cabinet is constructed of a vertically disposed panel 6, on the opposite sides of which 50 is arranged a pair of vertically disposed panels 7, thus forming a cross frame which is arranged to rotate upon the ball bearing 8 fixed in the center of the bottom 4; and the

upper end of this cross frame is pivotally supported upon a pin or screw 9, which 55 passes through the end of a bracket 10 secured to the frame 1, and which pin or screw also passes through a plate 11 fixed on top of the panels 7.

The panels 6 and 7 are provided in their 60 faces, at suitable distances apart, with the horizontally disposed grooves 12, in which are arranged the rear edges of segmental shelves 13, and the edges of which shelves 65 which project beyond the edges of the panels 6 and 7 are provided with grooves 14; and each adjacent or coinciding pair of grooves 14 receive a filler block, or key, 15, which prevents the outer edges of an adjacent pair 70 of the segments 13 from warping or varying 75 in elevation. Thus a series of circular shelves are formed on the frame, comprising the panels 6 and 7, and the edge of each shelf is provided with a rim 16, in the form of a sheet metal hoop, which is secured to the 80 outer edges of the segment 13 in any suitable manner, and which rim projects upwardly a short distance above the top surface of the shelf to prevent articles placed on the shelf for display from dropping off said shelf.

A display cabinet of my improved construction is very compact, conveniently holds a large number of articles, and all of the articles placed on the shelves of the rotary 85 member within the cabinet are readily discernible through the sides and top thereof, which are almost wholly composed of sections of plate glass, or like transparent material.

When the doors are open, the rotary mem- 90 ber of the cabinet, comprising the panels 6 and 7 and shelves carried thereby, can be easily shifted in either direction to bring any particular article to the front of the cabinet, from whence it can be removed.

The cabinets may be made in various sizes and forms to suit the different varieties of goods to be displayed.

I claim:—

A display cabinet, comprising a frame, 100 having transparent sides and top, transparent doors forming one of the sides of the frame, a vertically disposed cross frame arranged for rotation with the first mentioned frame, in the side faces of the members of which 105 cross frame are formed grooves, a series of

sets of segmental panels arranged in said grooves to form circular shelves, which panels project beyond the edges of the members of the cross frame, and the meeting edges of the projecting portions of said panels being grooved, and filler blocks located in the grooves formed in said panels.

In testimony whereof, I have signed my name to this specification, in presence of two subscribing witnesses.

FERDINAND D. MAGUOLO,

Witnesses:

M. P. SMITH,
E. L. WALLACE.
